UNITED STATES PATENT OFFICE.

IGNAZ BERGMANN, OF FORT MADISON, IOWA.

PEN GUIDE OR REST.

SPECIFICATION forming part of Letters Patent No. 402,796, dated May 7, 1889.

Application filed October 30, 1888. Serial No. 289,532. (No model.)

To all whom it may concern:

Be it known that I, IGNAZ BERGMANN, a citizen of the United States, residing at Fort Madison, in the county of Lee and State of Iowa, have invented a new and useful Improvement in Pen Guides or Rests, of which the following is a specification.

The invention relates to a pen guide or rest designed to insure the proper position of the pen-holder in the hand of the writer; and it consists in a certain novel construction and combination of parts, fully described herein-after in connection with the accompanying drawings, and specifically pointed out in the appended claims.

In the drawings, Figure 1 shows a hand with the improved pen-guide applied thereto in the operative position and the pen-holder engaged in the guide. Fig. 2 is a detail view 20 of the guide. Figs. 3, 4, 5, 6, and 7 represent different forms of the ring. Figs. 8, 9, and 10 represent still different forms.

Referring by letter to the drawings, A represents an elastic ring or band, preferably of 25 metal, which is cut or open at one side, and the free ends are bent to form the outward-extending eyes or knobs B B, which are adapted to be normally held in contact, as shown in Fig. 3, by the elastic loop or ring C, 30 which passes around the said eyes or knobs.

D represents a loose ring-shaped holder, which slides on the ring or band and adapted to have the pen-holder passed therethrough, and the said holder may be either of metal, rubber, or any other suitable material, but 35 preferably of rubber.

Fig. 3 of the drawings shows a slight modification of the pen-guide, in which one side of the ring or band is slotted or split, as shown 40 at E, and the holder is engaged in this slot and is thereby held out of contact with the forefinger of the writer.

Fig. 4 is a view of a similar modification, in which the side of the ring or band is split and the outer side, F, is freed or cut loose at one 45 end to enable the holder to be applied and removed at will. The free end of the side F is held in place when the holder is engaged in the slot by a loop or ring, C, similar to that 50 which is employed to hold the free ends of

the ring or band together in the form which is shown in Fig. 3.

Fig. 5 shows a simple form of the guide, in which the eyes or knobs at the free ends are omitted and the said ends are held in contact 55 by the elastic force of the metal or other material composing the ring or band, and Fig. 6 shows a still simpler form of the guide in which the ring or band is complete, thereby preventing the removal of the holder. 60

Fig. 7 shows a modification in which the holder is connected to the ring or band by an interposed link or connecting-ring, G.

The operation of the guide will be readily understood from the foregoing description. 65 The ring or band is placed on the forefinger of the writer, and the pen-holder is passed through the holder, and as the latter is held in contact with the forefinger and is allowed only a limited movement it will be evident 70 that the pen-holder cannot move out of the proper position. To prevent the ring or band from turning on the forefinger, the eyes or knobs are arranged under the second finger close to the main joint. 75

In Figs. 8, 9, and 10 very simple forms of the guide are shown. The ring or band in each of the said figures is complete, and notches or cuts or perforations are formed therein to receive the holder. In Fig. 8 the 80 notch or cut is formed in the outer side of the ring or band, in Fig. 9 it is formed in the inner side, and in Fig. 10 a small perforation is formed in the thickness of the ring or band.

I prefer to make the ring D of elastic material, as it will allow free movement of the pen-holder. 85

Having thus described the invention, I claim—

1. In a pen-guide, the ring or band to encircle the finger, and the elastic holder on the ring or band to receive the pen-holder, substantially as set forth. 90

2. In a pen-guide, the combination of the open-sided ring or band having eyes or knobs on its free ends, and the ring-shaped holder on the ring or band to receive the pen-holder, substantially as specified. 95

3. In a pen-guide, the combination, with a ring or band to encircle the finger, of an elas- 100

tic holder loosely connected to and sliding on the ring or band and adapted to receive the pen-holder, substantially as specified.

4. In a pen-guide, the combination of a split 5 ring or band, the elastic loop or ring C, engaging the free ends of the ring or band to draw them together, and the elastic ring-shaped holder connected to the ring or band to receive the pen - holder, substantially as 10 specified.

In testimony that I claim the foregoing as my own I have hereto affixed my signature in presence of two witnesses.

IGNAZ BERGMANN.
